(57) **CLAIM**

The ornamental design for beam joint hardware, as shown and described.

DESCRIPTION

FIG. 1 is a front elevation view of beam joint hardware showing the new design;

FIG. 2 is a left side elevation view thereof;

FIG. 3 is a right side elevation view thereof;

FIG. 4 is a top plan view thereof;

FIG. 5 is a cross-sectional view taken along line 5-5 shown in FIG. 1; and,

FIG. 6 is a front, side, top perspective view of two articles of beam joint hardware showing the new design, wherein the hardware is shown in its intended use with environmental structure.

FIG. 6 is included for reference purposes only and the environmental structure shown therein forms no part of the claimed design.

The broken lines represent environment and form no part of the claimed design.
